UNITED STATES PATENT OFFICE.

LUDY A. WARNER, JR., OF BUFFALO, NEW YORK, ASSIGNOR TO EDGAR W. WARNER, OF SAME PLACE.

DESIGN FOR AN INKSTAND OR SIMILAR ARTICLE.

SPECIFICATION forming part of Design No. 34,434, dated April 30, 1901.

Application filed April 4, 1901. Serial No. 54,398. Term of patent 7 years.

To all whom it may concern:

Be it known that I, LUDY A. WARNER, Jr., a citizen of the United States, residing at Buffalo, in the county of Erie and State of New York, have invented and produced a new and original Design for Inkstands or Similar Articles, of which the following is a specification, reference being had to the accompanying drawing, forming a part thereof.

10 This design relates to the configuration of an inkstand, paper-weight, or similar article of desk furniture.

The accompanying drawing is a perspective view of an inkstand embodying my design.

15 The leading feature of my design consists of the representation of a waterfall at one end of a substantially rectangular block which forms the main body of the inkstand or paper-weight.

20 Referring to the drawing, A is a block having a flat base *a*, a flat top *b*, parallel upright

sides *c*, and an end *d*, arranged at right angles to the sides, so that the block is substantially rectangular in form. At the opposite end *e* the block is formed so as to represent a waterfall, which descends from the flat top and spreads out endwise at the bottom in the form of waves. This waterfall is divided by a projection *f*, which represents rocks or land between two falling bodies of water. 25 30

g represents the ink-well.

What I claim is—

The design for an inkstand or similar article, substantially as herein shown and described. 35

Witness my hand this 29th day of March, 1901.

LUDY A. WARNER, JR.
